UNITED STATES PATENT OFFICE.

PRESTON M. BRUNER, OF ST. LOUIS, MISSOURI.

CONCRETE PAVEMENT.

SPECIFICATION forming part of Letters Patent No. 450,054, dated April 7, 1891.

Application filed May 21, 1889. Serial No. 311,589. (No specimens.)

To all whom it may concern:

Be it known that I, PRESTON M. BRUNER, of the city of St. Louis, in the State of Missouri, have invented a certain new and useful Improvement in Concrete Pavements, of which the following is a full, clear, and exact description, reference being had to the accompanying drawings, forming part of this specification, and in which—

10 Figure I is a plan view illustrative of my invention. Fig. II is a detail transverse section of two of the blocks. Figs. III and VI are diagrams made for the purpose of illustrating between my invention and what is old. 15 Fig. IV is a section similar to Fig. II, but showing the joint complete. Fig. V is a transverse section through a tool or instrument for forming the joints between the blocks. Fig. VII is a view of a tool in common use for 20 beveling the blocks at the joints. Fig. VIII is a vertical sectional view of a modification.

25 My present invention relates to that class of concrete pavements in which the material is put in place in a plastic or soft condition; and my invention consists in an improved 30 pavement of this kind, the joint being of such a character as to permit the blocks to move under expansion and contraction, due to different temperatures, and which will avoid the chipping or breaking of the blocks along the 35 upper edges, all of which will be more fully described hereinafter.

40 Referring to the drawings, 1 2 represent adjacent blocks of a pavement. 3 represents the scantling or strips used in forming the blocks for the purpose of keeping them rectangular or to preserve their symmetry. The old method of making such pavements is to place two of these strips 3 the distance apart 45 to make the desired size of block—that is, one of the strips would be placed as shown at A, Fig. 1, and the other at B. After the block 1 is made the strip at B is removed to C, and the block 2 is then made. It will be understood 50 that the cement "sets" very rapidly, so that after block 1 is formed and before block 2 is formed, block 1 has become sufficiently hardened so that block 2 will not become united or joined to it, although the material 55 of block 2 is placed up against block 1, which forms one of its walls, the strip 3 at C forming the other wall.

It has been customary to form the lower portion or body of the blocks of coarser material than the upper surface. This is illustrated in Figs. III and VI. It has also been customary to run a trowel along the joint between the two blocks after they have become sufficiently set, but before they are so hard as to prevent the passage of the trowel. This leaves a ragged space or joint between the upper portions of the two blocks, as shown at 55 5, Fig. III, which leaves the upper edges of the blocks, as shown at 6, Fig. III, acute or sharp, so that they are liable to become 60 chipped or broken off, which results in defacing the pavement. The object of passing the trowel between the blocks is to form a straight joint or line to well define the individuality of the blocks, and also serves the purpose of 65 allowing the blocks to expand in cold weather without breakage. To make clean and ornamental edges of the sharp edges at 6, as stated, it has been customary to run a V-shaped instrument (such as is shown in Fig. VII) 70 through the groove 5 at its upper end. This bevels off the edges of the blocks, as shown at 7, Fig. VI, but at the same time it forces a portion of the material into the groove 5 and closes it, as shown at 8, Fig. VI, and thus subjects the pavement to possible defacement at 75 joint and defeats the possibility of the expansion of the blocks without breakage, as it will not permit them to move toward each 80 other, but causes them to upheave. 85

Now the object of my invention is to form a real separate joint, instead of the old separable joints, by means of the slots 5 and bevels 8 without any disadvantage resulting therefrom. To this end I use a tool such as is shown 90 in Fig. V. It is provided with a tongue 9 projecting downward from a head 10, and at the point of connection between the tongue and head the tool is formed with an enlargement, as shown at 11. The tongue 9 forms the 95 grooves 5 between the blocks, the parts 11 true the upper end of the grooves, and the head 10 limits the downward movement of the tool, so that by pressing it firmly upon the blocks as it is drawn from end to end of the blocks, a 100 slot or groove of uniform depth is formed and the bevels or blunt corners 8 of uniform inclination are also formed. In this manner I am able to construct or make a pavement hav-

ing many advantages and none of the disadvantages heretofore existing, as above specified.

In the old method of making the grooves by means of a trowel their walls were ragged, as shown at Fig. III, and it very frequently happened that the trowel would be passed along to one side or the other of the natural joint, (or to one side or the other of the vertical wall of block 1,) which when frost came would cause two seams, one where the old-fashioned tool, Fig. VII, had been passed and the other directly over the natural joint, and the frost causing always a breakage at the true and natural joint. To avoid these ragged walls and misplacing of the joints by the tool I round or blunt the coarser or body parts of the blocks, as shown at 12, Figs. II and IV, and fill in the spaces between these blunt or rounded edges 12 with the finer top covering or coating, so that when the tool shown in Fig. V is introduced it is bound to seat directly over the natural joint, (there being less resistance in the finer than in the coarser material,) and the groove being made in the fine material, smooth instead of ragged walls are formed, and the joint is a true open joint separate and not separable.

I have shown the grooves formed by the tool extending not quite to the bottom of the blocks; but their depths may be varied, or they may extend entirely through or clear to the bottom of the blocks, as shown in Fig. VIII, and when not extending entirely through the part remaining will take any thrust between the blocks, and yet when any block is lifted the narrow rim easily breaks off under the transverse strain.

I claim as my invention—

1. An artificial stone pavement having open clear-cut grooves formed through the main body thereof and the upper edges of said grooves being beveled, and the material of the pavement composing the walls of said grooves and said bevels being worked or compacted to a greater density than the body of the pavement, substantially as set forth. 40 45

2. An improved pavement of the kind described, having a body portion or lower stratum formed with blunt edges at 12 and a coating or upper stratum having portions extending down between the blunted edges 12, said upper stratum having a groove extending through it, but not through the lower stratum, substantially as set forth. 50 55

3. An improved pavement of the kind described, having a coarser body portion beveled or rounded at 12 and a finer coating that extends down below the upper surface of the body portions and which is grooved, substantially as and for the purpose set forth. 60

4. An improved pavement of the kind described, having a body portion or lower stratum of coarse material, formed with blunt edges at 12, and an upper stratum or coating 1 of finer material projecting down between said blunt portions, said coating being grooved between said blunt portions, and said groove having beveled edges, substantially as set forth. 65

PRESTON M. BRUNER.

In presence of—

GEO. H. KNIGHT,
EDW. S. KNIGHT.
